CENTRIFUGAL PUMP

Filed April 30, 1945

UNITED STATES PATENT OFFICE

2,439,577

CENTRIFUGAL PUMP

Orlo Clair Norton, Erie, Pa.

Application April 30, 1945, Serial No. 591,023

6 Claims. (Cl. 103—113)

1

My present invention relates to pumps for handling air or water and a pump embodying the elements of my invention is capable of being operated either to compress air or create a vacuum in a conduit, or retort, equivalent to several inches of mercury in a manometer, or it may be used as a self priming water pump.

The above several objects of my invention are accomplished by the use of a rotary impeller circulating in a body of fluid and serving to divide the fluid into minute particles which will entrain air or other fluid particles, and force the mixture through a surrounding Venturi opening into a volute discharge conduit.

To these and other ends my invention embraces other improvements and arrangements of parts, all as will be described in the following specification, the novel features thereof being set forth in the appended claims.

In the drawings:

Fig. 1 is a side elevation, partly in section, showing one embodiment of my invention.

Fig. 2 is a face view of the impeller and,

Fig. 3 is an enlarged sectional view taken through one of the impeller discharge orifices as indicated by the section line 3—3 of Fig. 2.

Similar reference characters in the several figures indicate similar parts.

The apparatus embodies a hollow casing containing a rotary impeller and a chamber located at one side thereof, and containing a body of fluid such as water, which flows therefrom into the center of the impeller, and normally stands at a height level with the top of the impeller. Additional quantities of water are fed into the apparatus depending upon the service demands any excess thereof, flowing into the reservoir, being allowed to escape through a waste pipe.

The casing is a somewhat narrow hollow body composed of a base member 1, and a detachable cover or side piece 2, said parts being so shaped as to provide a surrounding volute discharge conduit 3, which is separated from the central chamber, containing the impeller, by a narrow restricted channel 4, the sides of which are gently curved to give it, in cross section, the shape of a Venturi tube. Leading into one side of the central chamber is an inlet 5 which, in the event the apparatus is to be operated as a vacuum pump, will be connected to the retort or chamber from which air is to be exhausted. In such cases, I introduce at one side of inlet 5, a pipe 6 through which additional small quantities of water may be allowed to flow. In the

event the apparatus is to be used for pumping water, the inlet 5 will be extended, as indicated by dotted lines, into a well or other source from which water is to be obtained.

At the other side of the pump body there is located a priming reservoir 10, having at the bottom of its side wall a tangential opening 11, connected by a pipe 12, to the center of the body chamber. The bottom of the reservoir 10, is formed by a plate 13 which spirals downwardly from the top of the opening 11, to its bottom edge for the purpose of facilitating a circular movement of the water in the reservoir. The circular volute discharge is connected at its top, as indicated by 14, with the side of the reservoir which is opposite its outlet opening 11. In the center of the reservoir is a waste pipe 15, the top of which is level with the top of the impeller rim, and resting thereon is a ball 16, which acts as an overflow check. It is normally retained in a central position in the reservoir by the cavitation created by the swirling of the water in the tank and lifted to open the overflow when the volume of water rises above the top of the waste pipe. The tank is vented through a pipe 17 from which the exhausted air escapes.

The impeller is mounted on a driven shaft 20, carried in bearings 21 at one side on a lateral projection of the body 1 and at its other side, the rim on its hub 22 fits a central opening of the cover 2, surrounding the inlet 12, its position therein being maintained by a spring 23. The impeller is formed of a back plate 25, which carries a hub portion fitted on the end of the shaft 20, and a front plate 26. Both of these plates are circular and surrounding them is a ring 27 which is provided with closely located radial perforations to form a large number of discharge nozzles 28. The latter taper inwardly into communication with the hollow center of the impeller.

For the purpose of deflecting the fluid within the impeller outwardly I form on the back plate 25, a series of ribs 29, which are preferably curved and tapered toward their extremities. In order also that equal quantities of water and air may at all times exist on both sides of the impeller, I provide passages therethrough by making comparatively large openings in each of the ribs 29. These are indicated by 30, and extend at an angle upwardly from hub on the rear face of plate 25, and through the front plate 26.

It will be observed in Fig. 2 that the tip of each of ribs 29 terminates short of the periphery of

each of the plates 25 and 26, thus providing annular channels for the free flow of fluid between them, some of which will find escape through the nozzles 28. In order to direct the fluid positively into each nozzle, I locate at the trailing edge of each of them a small projection 31 (see Fig. 3) which is formed as a rib or lip, integral with and extending laterally from the periphery of the front plate 26. These lips serve to entrain the fluid in its outward movement in the impeller and direct it into the respective orifices 28. The resulting action is that the fluid is expelled with great force in continuous fine streams.

The continuous discharge of fluid under pressure from the rim of the impeller into the Venturi opening creates a suction which draws air into the intake 5. The discharge end of the latter is below the normal fluid level, consequently aeration of the fluid surrounding the impeller ensues so that the movement of comparatively large quantities of air is facilitated as additional small quantities of water are supplied from the source 6.

The fluid introduced into the impeller is also aerated for the purpose of breaking up the streams of fluid emitted from the nozzles 28, into globules for the purpose of greater entrainment of air as the mixture of air and fluid surrounding the impeller is driven through the Venturi opening. As this resulting mixture expands in the volute conduit, it escapes into the reservoir 10, the excess water flowing out of the waste pipe and the air passing away through the opening 17. When the apparatus is in operation the fluid in the reservoir is in a violent state of ebullition, so that in most instances it is not necessary to supply air thereto to produce the globular effect in the nozzle streams. However, where this is desirable, and to facilitate a quick starting of the apparatus, I provide for the introduction of a small stream of air into the entrance opening at the forward side of the impeller by means of an air pipe 35. This leads from the lower side of a valve casing 36, connected to the top of the reservoir by a pipe 37. A normally closed needle valve 38 is controlled by a diaphragm 39, working against an adjustable spring tension 40.

I claim as my invention:

1. In a centrifugal pump, the combination with a casing having an intake chamber for receiving air and fluid provided with a surrounding Venturi shaped outlet, a volute conduit leading therefrom, of a hollow impeller provided with jet orifices discharging into said venturi, a reservoir, an inlet conduit connecting the volute conduit with the upper portion of the reservoir and an outlet conduit connecting the reservoir at a lower point with the interior of the impeller.

2. In a centrifugal pump, the combination with a casing having an intake chamber for receiving air and fluid provided with a surrounding Venturi shaped outlet, a volute conduit leading therefrom, of a hollow impeller provided with jet orifices discharging into said venturi, a reservoir, an inlet conduit connecting the volute conduit with the upper portion of the reservoir and an outlet conduit connecting the reservoir at a lower point with the interior of the impeller, and inlet and outlet conduits tangentially connected to opposite sides of the reservoir at different levels, the former leading from the volute conduit and the latter connected to the impeller.

3. In a centrifugal pump, the combination with

a casing having an intake chamber for receiving air and fluid provided with a surrounding Venturi shaped outlet, a volute conduit leading therefrom, of a hollow impeller provided with jet orifices discharging into said venturi, a reservoir having an outlet at one side, a bottom in the reservoir spiralling upward from the bottom of said outlet, a conduit connecting the latter with the interior of the impeller, and a conduit connecting the volute conduit with the reservoir at a point above its outlet.

4. In a centrifugal pump the combination with a casing having an intake chamber for receiving air and fluid provided with a surrounding opening of Venturi shape, a hollow impeller journaled to rotate in a vertical plane having jet discharge nozzles in its periphery discharging into said venturi, of a reservoir located at one side of said casing, a conduit connecting it with the interior of the impeller, a waste pipe leading from the reservoir at approximately the level of the top of the impeller, and a conduit communicating with said venturi and discharging tangentially into the reservoir at a point above the level of the waste pipe, and a valve controlling the outflow from said pipe which is opened and closed by the action of the fluid discharged into the reservoir.

5. In a centrifugal pump the combination with a casing having an intake chamber for receiving air and fluid provided with a surrounding opening of Venturi shape, a hollow impeller journaled to rotate in a vertical plane having jet discharge nozzles in its periphery discharging into said venturi, of a reservoir, a conduit connecting it with the interior of the impeller, an open ended waste pipe leading from the center of the reservoir, a conduit leading from the venturi to one side of the reservoir above the waste pipe and a float valve regulating the discharge therefrom automatically controlled by the rise and fall of the fluid discharged into the reservoir.

6. In a centrifugal pump the combination with a casing having an intake chamber for receiving air and fluid provided with a surrounding opening of Venturi shape, a hollow impeller journaled to rotate in a vertical plane having jet discharge nozzles in its periphery discharging into said venturi, of a reservoir, a conduit connecting it with the interior of the impeller, a centrally located open ended waste pipe leading from the center of the reservoir on a level approximately that of the top of the impeller, a conduit connecting a lower point of the reservoir with the impeller, a second conduit leading from the venturi and discharging into the reservoir in a tangential direction to create a vortex in the fluid therein and a float riding in the vortex and movable by the rise and fall of the fluid to control the escape of fluid through the waste pipe.
